UNITED STATES PATENT OFFICE

121,576

DESIGN FOR A CORN PAD OR THE LIKE

William M. Scholl, Chicago, Ill.

Application June 3, 1939, Serial No. 85,318

Term of patent 14 years

To all whom it may concern:

Be it known that I, William M. Scholl, a citizen of the United States and a resident of the city of Chicago, in the county of Cook and State of Illinois, have invented a new, original, and ornamental Design for a Corn Pad or the like, of which the following is a specification, reference being had to the accompanying drawing, forming a part thereof.

On the drawing:

Figure 1 is a top plan view of the corn pad or the like showing my new design;

Figure 2 is a bottom view; and

Figure 3 is a side elevational view thereof.

The characteristic features of my design reside in a corn pad or the like substantially of the configuration shown having a cover member with a serrated edge disposed on the body member of the pad, and with the serrated edge of the cover member set back from the edge of the body member, substantially as shown.

I claim:

The ornamental design for a corn pad or the like, as shown and described.

WILLIAM M. SCHOLL.
